SPRAYING DEVICE

William Clayton, Pasadena, Calif., assignor to
 Clayton Manufacturing Company, Alhambra,
 Calif., a corporation of California

Application June 9, 1936, Serial No. 84,259

12 Claims. (Cl. 299—107)

My invention relates to a device for spraying hot liquids, which, due to the heated condition, tend to form gases or steam on being released from pressure in a spray nozzle, and the invention relates in particular to means for spraying a hot detergent against a surface which is to be cleaned thereby.

My present invention is an improvement on or an addition to the invention disclosed in application Serial No. 495,636, filed November 14, 1930, by Walter S. Kerrick, for a "Fluid heater."

The invention is of especial utility in the cleaning of surfaces, such, for example, as the walls of buildings, floors, etc., by the application of a detergent solution thereto which may consist of a mixture of soap and water heated to a temperature near the boiling point of water. It has been found that surfaces of the general character above set forth can be cheaply and expeditiously cleaned by the application of a stream of detergent solution under heat and pressure, and I have determined that maximum efficiency in this cleaning action can be maintained where the issuing jet of heated detergent solution is held under control and in a concentrated form.

Naturally, in the operation of a device of this character, the greater the heat of the detergent solution the more effective will be the cleaning action; but, considerable difficulty has been experienced where the detergent solution is raised to or above the boiling point due to the tendency for steam to form in relatively large quantities or clouds adjacent the discharge orifice of the ordinary type of spray nozzle used with the device, these clouds of steam interfering with the operator's view of the surface being treated and causing a sputtering action of the fluid as it issues from the discharge orifice of the nozzle.

It is an object of my present invention to provide a cleaning device of the above character having means for delivering the hot detergent solution in such a manner that the formation of steam around the discharge of the nozzle will be reduced to a minimum and so that the undesirable sputtering of the discharging fluid will be eliminated.

A further and important object of the invention is to provide a cleaning device of the above character having a discharge nozzle which will deliver a stream containing vapor and liquid in slender, concentrated form and of flattened cross-sectional area.

It is a further object of the invention to provide a nozzle which will issue a fluid jet of flattened form, this nozzle having a tubular external

wall of flattened or rectangular cross section and having a core therein of flattened form to define a tubular discharge passage and also a tubular discharge orifice of flattened or rectangular cross section.

Further objects and advantages of the invention will be made evident throughout the following part of the specification.

Referring to the drawing, which is for illustrative purposes only,

Fig. 1 is an elevational view of a cleaning device embodying my present invention.

Fig. 2 is an enlarged sectional view showing a preferred construction of nozzle for use in conjunction with the device pictured in Fig. 1.

Fig. 3 is an end view of the nozzle shown in Fig. 2, this view being taken as indicated by the line 3—3 of Fig. 2.

Fig. 4 is a cross section on a plane represented by the line 4—4 of Fig. 2.

Fig. 5 is a cross section through the fluid jet taken on a plane indicated by the line 5—5 of Fig. 2.

Fig. 6 is a front end view of an alternative form of nozzle embodying my invention.

In Fig. 1, I show a cleaning device 11 which includes a tank 12 for a detergent solution, such, for example, as a mixture of soap and water. Through a pipe 13 the detergent solution is carried to a force pump 14 which delivers the detergent solution through a pipe 15 to a heater 16 having a discharge member 17 to which a discharge conduit 18, including a hose 19 and a pipe 21, may be secured. The pipe 21 is suitably insulated so that it may be handled, and to the forward end thereof a nozzle 22 is secured, this nozzle 22 being so formed that a relatively slender jet 23 of the detergent solution will issue therefrom. I find that with my present invention I can heat the detergent solution to nearly 300° F., which is considerably above the boiling point of water at atmospheric pressure, and yet maintain a slender jet 23; whereas, the natural tendency for the heated solution is to expand on issuing from the nozzle so as to form a jet such as indicated by dotted lines 24. Likewise, where ordinary types of nozzles are employed, there will be a formation of clouds of steam ahead of the discharge nozzle, and the heated detergent will issue from the nozzle with a sputtering action. However, by using a nozzle of the character shown in Figs. 2 to 5 inclusive, I am enabled not only to use the detergent solution at a high temperature, but also to maintain a relatively slender concentrated

jet 23 which is of flat cross-sectional form, as shown in Fig. 5, and is not accompanied by large clouds of steam which will interfere with the vision of the operator. The expanded jet obtained by use of ordinary nozzles with a device of the character shown results in a rapid loss of the force of the fluid upon its issue from the nozzle, thereby making it necessary to hold the nozzle relatively close to the work if any reasonable force of application of the heated detergent fluid to the surface to be cleaned is to be obtained. The condensed jet 23, in addition to being of flat character or laterally expanded, is of such concentration that it will carry for a considerable distance and will cause the detergent solution to strike the surface to be cleaned with considerable force.

The nozzle disclosed in Figs. 2 to 4 inclusive comprises a tubular wall 25 having a threaded 20 inlet opening 26 for attachment to the forward end of the pipe 21, and having a discharge opening 27 at its opposite end. Within the tubular wall 25 a core 28 is extended, the wall 25 and the core 28 being so formed that between them there 25 will exist a tubular passage 29 of flattened, and preferably rectangular, form. Although I find that satisfactory results can be obtained in the nozzle where the passage 29 is of substantially constant cross section from end to end thereof, it 30 is preferable to make the core 28 in the form of a flat bar of substantially constant cross section from end to end thereof, and to taper the wall 25 forwardly so that the passage 29 will reduce in cross-sectional area toward the discharge 35 opening 27. The forward end 31 of the core 28 extends preferably centrally within the discharge opening 27 so as to form therein a discharge orifice 32 of flattened tubular form. The rearward end 35 of the core 28 extends within an opening 36 at the rearward end of the wall 25, and is adjustably secured by means of screws 37. The forward end 31 of the core 28 is relatively blunt and preferably has a flat front face 38 placed so that it will not project materially beyond the 40 front end face 39 of the wall 25, and being preferably set back from the end 39 inside the discharge opening 27 in the manner shown in Fig. 2, in which position the best operation of the spraying device is obtained. When the flow of 45 detergent solution issues at high velocity from the tubular orifice 32, it is caused to converge in the manner shown by lines 40 of Fig. 2, with the result that the smallest part of the jet 23, as indicated by the numeral 41, will be at a distance from the end of the nozzle. This effect is apparently caused by the formation of a wedge-shaped 50 vacuum space 42 adjacent the end face 38 of the core 28. As a result of the conditions above set forth, a relatively slender jet 23 of the heated 55 solution is formed, and the force thereof is concentrated to such a degree that the jet will carry a considerable distance and will strike the surface to be cleaned with considerable force. Likewise, the popping or sputtering of the jet is overcome so that the action of the nozzle is relatively quiet. Likewise, the liberation and separation of steam adjacent the nozzle is minimized, with the 60 result that the operator's view of the surface being cleaned is not obstructed to such an extent as to interfere with the carrying on of the work.

I have found that the discharge orifice 32 does not have to be fully tubular; or, in other words, the orifice need not extend around all four sides of the forward end portion 31 of the core 28 in the manner shown in Fig. 3. Instead, the dis-

charge orifice may extend on two sides or around three sides of the core in the manner shown in Fig. 6, wherein I have shown the front end 39a of a nozzle 22a, having a rectangular opening 27a with a flat core 28a therein in such position 5 that it engages or is attached to opposing edge walls 44 of the nozzle shell 25a. The core 28a forms in the rectangular opening 27a a divided orifice 32a which extends across the top and then across the bottom of the core 28a. Even though 10 the discharge orifice 32a is not completely tubular, a vacuum pocket of wedge-shape will be formed adjacent the forward end of the core 28a, causing a concentration of the jet beyond the end of the nozzle 22a. If desired the orifice 32a may 15 extend across one edge wall of the core 28a, as indicated by the dotted line 30 of Fig. 6. In this construction the orifice will be of U-shaped cross section.

Although I have herein shown and described 20 my invention in simple and practical form, it is recognized that certain parts or elements thereof are representative of other parts, elements, or mechanisms which may be used in substantially the same manner to accomplish substantially the 25 same results; therefore, it is to be understood that the invention is not to be limited to the details disclosed herein but is to be accorded the full scope of the following claims.

I claim as my invention:

1. A device of the character described for delivering a concentrated jet, including: a tubular wall having one end thereof disposed so as to receive a stream of fluid and having the other end thereof forming a discharge opening of flattened cross section; and a core of flattened cross section extending axially within said tubular member so as to form a tubular passage therein, said core extending into said discharge opening to define therein a tubular discharge orifice and terminating in a relatively flat end surface whereby said fluid stream creates a zone of reduced pressure adjacent said relatively flat end surface tending to draw the resulting jet together.

2. A device of the character described for delivering a concentrated jet, including: a tubular wall having one end thereof disposed so as to receive a flow of fluid and having the other end thereof forming a discharge opening of flattened cross section, said discharge opening having a width at least twice as great as its height; and a core of flattened cross section extending axially within said tubular member so as to form a tubular passage therein, said core extending into said discharge opening and defining therein a tubular discharge orifice.

3. A nozzle of the character described for delivering a concentrated stream of fluid, including: a tubular wall having a fluid inlet at one end thereof and a discharge opening at the other end thereof of flattened cross section; and a core extending axially within said tubular member so as to form a tubular passage therein, the forward end of said core being of flattened cross section 60 and forming a tubular discharge orifice in said discharge opening.

4. A nozzle of the character described for delivering a concentrated stream of fluid, including: a tubular wall having a fluid inlet at one end 70 thereof and a discharge opening at the other end thereof of flattened cross section; and a core extending axially within said tubular member so as to form a passage therein, the forward end of said core being of flattened cross section and 75

forming in said discharge opening a discharge orifice which extends around at least three sides of said forward end of said core.

5. A nozzle of the character described for delivering a concentrated stream of fluid, including: a tubular wall having a fluid inlet at one end thereof and a discharge opening at the other end thereof of rectangular cross section; and a core extending axially within said tubular member so as to form a tubular passage therein, the forward end of said core being of rectangular cross section and forming a tubular discharge orifice in said discharge opening.

6. A nozzle of the character described for delivering a concentrated stream of fluid, including: a tubular wall having a fluid inlet at one end thereof and a discharge opening at the other end thereof of rectangular cross section; and a core extending axially within said tubular member so as to form a passage therein, the forward end of said core being of rectangular cross section and forming in said discharge opening a discharge orifice which extends around at least three sides of said forward end of said core.

25 7. A nozzle of the character described for delivering a concentrated stream of fluid, including: a tubular wall having a fluid inlet at one end thereof and a discharge opening at the other end thereof of flattened cross section; and a core extending axially within said tubular member so as to form a passage therein, the forward end of said core being of flattened cross section and forming in said discharge opening a discharge orifice which extends on at least two sides of said forward end of said core.

35 8. In combination in a device for forming a concentrated steam-containing jet: a tubular wall providing a zone adapted to receive at one end a flow of fluid and forming at its other end a discharge opening of flattened cross section; and a core of flattened cross section extending substantially axially in said tubular wall to form discharge passage means between the sides of said core and the side walls of said discharge opening, the forward end of said core terminating near the forward end of said tubular wall and providing a relatively blunt end whereby flow of a fluid stream containing steam through said discharge passage means and past said blunt end sets up a zone of reduced pressure beyond said blunt end to control the shape of the resulting steam-containing jet and bring the flow through said discharge passage means together at a point beyond said blunt end of said core.

55 9. A combination as defined in claim 8 in which

said discharge passage means on opposite sides of said flattened core are non-parallel and converge toward each other as they approach the position of said relatively blunt end to assist the action of said zone of reduced pressure in bringing the flow therethrough together at said point beyond said blunt end of said core.

10. A nozzle of the character described for discharging a concentrated jet, including: a tubular wall providing a zone receiving fluid at one end and providing a discharge opening at its other end of flattened cross section providing side walls; and a core extending in said zone and providing a flattened forward portion cooperating with the flattened side walls of said discharge opening to form a discharge passage means on opposite sides of said core for delivering flattened streams toward and beyond the forward end of said core, said forward end of said core terminating near said discharge opening and being relatively blunt whereby flow of said flattened streams past said relatively blunt end forms a zone of reduced pressure adjacent this relatively blunt end to control the shape of the resulting jet and bring the flattened streams together at a point beyond said relatively blunt end of said core.

11. A nozzle of the character described for discharging a concentrated jet, including: a tubular wall providing a zone receiving fluid at one end and providing a discharge opening at its other end which discharge opening is of elongated shape in cross section; and a core extending in said zone and providing a forward portion elongated in cross section similar to the cross sectional shape of said discharge opening except smaller to provide an elongated annular passage means around said forward elongated portion of said core and inside said tubular wall, said forward elongated portion of said core terminating near the forward end of said discharge opening and providing a relatively blunt end surface beyond which the stream flowing through said elongated annular passage moves, the resulting elongated annular stream flowing past said relatively blunt end surface forming a zone of reduced pressure adjacent this end surface to control the shape of the resulting jet and bring the elongated annular stream together at a point beyond said relatively blunt end surface of said core.

12. A combination as defined in claim 1 in which said discharge opening is of rectangular cross section and in which said core is of rectangular cross section.

WILLIAM CLAYTON. 55
